CLAIM

The ornamental design for a wedge base lampholder for use on track, as shown and described.

DESCRIPTION

FIG. 1 is a perspective view showing the bottom of the wedge base lampholder for use on track showing our design with a lamp shown in dotted form mounted in the lampholder;

FIG. 2 is a perspective view showing the top of the wedge base lampholder for use on track shown in FIG. 1 on an enlarged scale with a lamp shown in dotted form;

FIG. 3 is a front elevational view of the wedge base lampholder for use on track shown in FIG. 1 on an enlarged scale;

FIG. 4 is a right side elevational view of the wedge base lampholder for use on track shown in FIG. 1 on an enlarged scale with a lamp shown in dotted form mounted in the lampholder, and the left side elevational view being a mirror image of the right side;

FIG. 5 is a rear elevational view of the wedge base lampholder for use on track shown in FIG. 1 on an enlarged scale;

FIG. 6 is a top view of the wedge base lampholder for use on track shown in FIG. 1 on an enlarged scale; and,

FIG. 7 is a bottom view of the wedge base lampholder for use on track shown in FIG. 1 on an enlarged scale with a lamp shown in dotted form mounted in the lampholder.

The lamp is shown in dotted lines for illustrative purposes only and forms no part of the claimed design.
